United States Patent Office

Des. 177,495
Patented Apr. 24, 1956

177,495

TOY SUSPENSION RAILWAY SECTION

Arthur J. Di Stasi, Trenton, N. J.

Application August 15, 1955, Serial No. 37,475

Term of patent 14 years

(Cl. D34—15)

The figure is a perspective view of a toy suspension railway section embodying my new design, the opposite sides of which are substantially similar to that shown.

I claim:

The ornamental design for a toy suspension railway section, substantially as shown and described.
